W. J. TOWLE

METHOD OF FORMING GASKETS AND APPLYING THE SAME TO CAN NECKS, ETC

Filed Apr. 17, 1922

Patented Feb. 20, 1923.

1,446,025

UNITED STATES PATENT OFFICE.

WILLIAM J. TOWLE, OF ST. PAUL, MINNESOTA.

METHOD OF FORMING GASKETS AND APPLYING THE SAME TO CAN NECKS, ETC.

Application filed April 17, 1922. Serial No. 553,609.

To all whom it may concern:

Be it known that I, WILLIAM J. TOWLE, citizen of the United States, resident of St. Paul, in the county of Ramsey and State of Minnesota, have invented certain new and useful improvements in method of forming gaskets and applying the same to can necks or other nozzles and mechanism therefor, of which the following is a specification.

10 This invention relates to a new method of cutting out gaskets, preferably of paper, and applying them to nozzles, such as sheet metal can necks, so that when said nozzles are united to the can bodies the joints between 15 the nozzles and can bodies will be tight and non-leakable.

One object of the invention is to employ the wall of the nozzle as a cutter or die, for cutting out the center of the gasket, the gasket, by the same operation, being seated on the can nozzle, and preferably remaining thereon until the nozzle is applied to a can body, when the gasket will be seated between the outer wall of the can body and a flange 25 on the nozzle to form a tight joint between said body and said can nozzle.

Another object of the invention is to provide means for quickly and accurately cutting out said gaskets, using the nozzle as a 30 cutter, and applying them to said can nozzles.

The invention consists generally in the method or process, and in the constructions and combinations hereinafter described and 35 particularly pointed out in the claims.

In the accompanying drawings forming part of this specification,

Figure 1 is a partial sectional view of a machine that may be employed for carrying 40 out my invention, showing a nozzle and a strip of gasket material in position on the lower die;

Figure 2 is an enlarged detail view, showing the means for centering the nozzle on 45 the lower die;

Figure 3 is a detail view, showing the means for burring or folding the upper flange of the nozzle;

Figure 4 is a view similar to Figure 3, 50 showing the means for cutting out the central portion of the gasket;

Figure 5 is a view similar to Figures 3 and 4, showing the gasket completely formed and severed from the gasket strip and also 55 the means for upsetting or folding the bead on the can neck;

Figure 6 is a detail view, showing the completed can neck, with the gasket applied thereto.

In the drawings, referring to Figure 1, 2 60 represents the bed plate of a suitable machine, and 3 the usual ram or plunger to which the upper die, hereinafter described, is secured. A die block 4 is secured to the bed plate 2 by bolts 5 and is provided with 65 a recess 6 in its upper face. A lower die 7 (Figure 1) having an annular flange 8 is provided within the recess 6, and secured to the die block 4 by screws 9, preferably four in number. The die 7 is preferably arranged 70 with its upper or cutting edge on a line with the face of the die block 4. Within the said recess I also provide a stripper plate 10, yieldingly and loosely located around the die 7 supported by pins 11, preferably four in 75 number, and compression springs 12, in sockets 13, provided in the die block 4. A center block 15 having a reduced portion 14 and a shoulder 16, is preferably provided within and below the die 7, and is yieldingly 80 held in its upper, or normal, position by pins 17 and 18, plates 19, a rubber cushion 20, and stud bolts 21, secured to the bed plate 2 the shoulder 16 limiting the upward movement of said block 15. When the center block 15, 85 and the stripper plate 10, are in their upper positions, as shown in Figure 1, a smooth surface is provided over the face of the die block 4, to permit the strip 22 of paper or other gasket material to be fed into the machine without interference. In this figure I have shown a gasket strip 22, and a can neck 90 23, positioned for the cutting and forming operation. I have not shown any means for feeding the gasket strip 22, and the can neck 95 23, into the machine, as the means used for this purpose may be of any suitable type and construction.

Referring to the upper part of the machine (Figure 1) a die block 24 having a stem 25, is secured to a suitable plunger 3, in any suitable way. I have indicated the plunger in Figure 1, but have shown no operating means. Such means will be employed and may be of any well-known type and construction, not necessary here to be illustrated.

An upper cutting die 26 is preferably provided with a cutting edge 26^a and is secured to the block 24 by suitable means, such as 110 bolts 27. A flange forming member 28 is also secured to said die block by suitable

bolts 29, preferably four in number. A rod 30, carrying a burring or upsetting tool 31, is slidably mounted in the stem 25 of the die block 24, and is held in its normal position, as shown in Figure 1, by a pin 32 bearing against a collar 33 resting on the stem 25. The collar 33 is provided with knock-out pins 34, preferably three in number, to actuate a pressure or knock-out sleeve 35, 10 slidably mounted in the forming member 28, and on the burring tool 31, a shoulder 31^a being provided on the burring tool to limit the downward movement of the knock-out sleeve 35.

15 When the cutting and forming operation is started, the plunger 3 commences a downward movement, and when it gets to the position shown in Figure 2, the lower end portion 31^b of the burring tool 31, of slightly 20 smaller diameter than the opening provided by the inturned flange 23^a on the can neck, enters said opening, thereby providing a positive centering means for the can neck on the lower die. In this figure the knock-out sleeve 35 is also shown resting on the can neck. In Figure 3 the flange 23^a of the can neck is shown turned down, and the forming member 28, bearing on the bead 23^b of the can neck securely holds said can 25 neck in its centered position during the actual gasket cutting operation. The can neck is here shown positioned on the strip of gasket material resting on the lower cutting die 7. It will also be seen that the 30 outside diameter of the lower vertical flange 23^c of said can neck, is of substantially the same diameter as the inside diameter of the lower cutting die 7. As the plunger 3 proceeds in its downward movement the can 35 neck, acting as a shearing punch, is forced through the gasket strip, thereby shearing said strip between the lower edge of the flange 23^c and the inner cutting edge of the lower cutting die 7, thus cutting out the 40 central portion 22^a of the gasket material. During this part of the operation the can neck carries with it the center block 15, until it preferably contacts with the bottom of the socket in the die block 4, providing a positive stop and preventing further downward movement of the flange 23^c of the can neck.

45 In Figure 3 the can neck is shown in position for the gasket cutting operation, and 50 also in position for the bead upsetting operation. In this figure it will be noted that the inside diameter of the cutting edge 26^a of the upper cutting die 26, is of substantially the same form and diameter as the 55 outside diameter of the lower cutting die 7, thus providing a shearing means for cutting the outer circumference of the gasket.

60 As the plunger 3 continues in its movement from the position shown in Figure 3

to that shown in Figure 4, the center of the gasket is cut as above described. A further movement of the forming member 28, bearing on the bead 23^b of the can neck, 70 folds or upsets the bead as shown in Figures 5 and 6. The knock-out sleeve 35 also acts as a pressure sleeve during the operation of upsetting the bead, bearing against the top of the can neck with its lower edge (Figures 4 and 5) and against 75 the die block 24 at its upper end.

As the plunger passes from the position shown in Figure 4 to that shown in Figure 5 the cutting edge 26^a of the die 26 cooperates with the outer edge of the lower 80 die 7, shears off the outer edge of the gasket, the stripper plate 10 moving downward under pressure of said die.

When the parts reach the positions shown in Figure 5 the operation of the machine 85 is complete and the nozzle with the gasket applied will be in the form shown in Figure 6.

90 The lower vertical flange 23^c of the can neck is preferably knurled, as shown in Figure 6, thereby providing a better cutting or shearing edge, and also providing a slightly irregular surface to prevent the gasket from separating from the can neck during the process of handling.

95 When the plunger starts its upward or return stroke, the can neck, being held in the forming member 28 by friction, is carried with it until the knock-out pins 34 are encountered, thereby ejecting the complete 100 can neck, with the gasket applied thereto, from the machine. A coiled spring 36, secured to the burring tool 31 is provided for ejecting from the can neck the central portion 22^a of the gasket. Also the stripper 105 plate 10 assumes its normal position thereby positioning the paper strip to be fed into the machine for the next operation.

110 The mechanism for operating the knock-out pins 34 and the rod 30 may be of any well known type and construction, such as suitable operating arms 40 and 41 (Figure 1) actuated by any suitable means, which I have not thought necessary to show herein.

115 By this improved method of forming and applying gaskets to can necks or other nozzles, the upper usual shearing punch is dispensed with, the can neck functioning as a punch, thereby simplifying the construction of the machine, and each nozzle is its own new cutting punch.

120 Also gaskets applied to can necks or other nozzles as above described, are snugly fitted to the can necks due to the improved method 125 of forming and applying the gaskets in the one operation, thereby eliminating the usual objectionable feature of the gaskets becoming separated from the can necks and lost in handling before being positioned on the 130

can bodies, as is the case with gaskets made with two regulating cutting dies in a separate operation and afterwards applied to the nozzles by hand.

- 5 While I have referred to the gaskets as being made of "paper" it will be understood that I do not limit myself to any particular material for said gaskets. Any suitable material may be employed for this
 10 purpose and will be understood as coming within the scope of the specification and claims.

It will also be understood that I do not limit myself to the particular details of construction shown and described, but that various equivalent constructions and modifications of details may be made without departing from the principle and scope of the invention.

- 20 I claim as my invention:

1. The method of forming gaskets and applying the same to can nozzles or similar structures, consisting in supporting a strip of gasket material, bringing the edge of a can nozzle against said strip, forcing the edge of the nozzle through said strip, and thereafter cutting the outer gasket edge to form a complete gasket and leave the same positioned on said nozzle.
 30 2. The method of forming gaskets and applying the same to can nozzles or similar structures, consisting in supporting a strip of gasket material, bringing the edge of a can nozzle against said strip, forming a flange on the outer surface of said nozzle and forcing the edge of the nozzle through the gasket strip, and bringing the strip against said flange, and thereafter cutting the outer gasket edge to form a complete
 35 gasket and leave the same positioned on said nozzle in contact with said flange.

40 3. The method of forming gaskets and applying the same to can nozzles or similar structures, consisting in supporting a strip of gasket material, bringing the edge of a can nozzle, having a peripheral bead on its outer surface, against said strip, forcing the edge of the nozzle through the gasket strip and simultaneously pressing said bead into an outwardly projecting flange, bringing the strip against said flange, and thereafter cutting the outer gasket edge to form a complete gasket and leave the same positioned on said nozzle in contact with said flange.

45 4. The method of forming gaskets and applying the same to can nozzles or similar structures, consisting in bringing the edge of a can nozzle against a suitably supported strip of gasket material, forcing the edge of the nozzle through said strip, and cutting the outer gasket edge to form a complete gasket and leave the same on said nozzle.

50 5. The method of forming gaskets and applying the same to can nozzles or similar structures, consisting in bringing the edge

of a can nozzle, having an outwardly extending flange, against a suitably supported strip of gasket material, forcing the edge of the nozzle through the gasket strip and bringing the strip against said flange, 70 and cutting the outer gasket edge to form a complete gasket and leave the same positioned on said nozzle in contact with said flange.

6. The method of forming gaskets and applying the same to can nozzles or similar structures, consisting in bringing the edge of a can nozzle having a knurled edge, against a suitably supported strip of gasket material, forcing the edge of the nozzle 75 through the gasket strip and bringing the strip against said flange, cutting the outer gasket edge to form a complete gasket, and leave the same positioned on said nozzle in contact with said flange.

7. Mechanism for forming gaskets and applying the same to can nozzles or similar structures, comprising, in combination, means for supporting a strip of gasket material, means for positioning a can nozzle 90 thereon, means for forcing the edge of the nozzle through said gasket strip, and means for cutting the outer edge of the gasket, whereby a gasket is formed and positioned on said nozzle.

8. Mechanism for forming gaskets and applying the same to can nozzles or similar structures, comprising, in combination, means for supporting a strip of gasket material, means for positioning a can nozzle 100 thereon, means for forming an outwardly projecting flange on said nozzle, means for forcing the edge of the nozzle through said gasket strip, and bringing said strip against said flange, and means for cutting the outer edge of the gasket, whereby a gasket is formed and positioned on said nozzle against said flange.

9. Mechanism for forming gaskets and applying the same to can nozzles or similar structures, comprising, in combination, means for supporting a strip of gasket material, means for positioning a can nozzle thereon, means for centering the can nozzle and forming a burr at its upper end, and 110 means for forcing the other end of the nozzle through the gasket strip, and means for cutting the outer edge of the gasket.

10. Mechanism for forming gaskets and applying the same to can nozzles or similar structures, comprising, in combination, means for supporting a strip of gasket material, means for positioning on said strip a can nozzle having a peripheral bead on its outer surface, means for pressing said bead into an outwardly extending flange and forcing the edge of the nozzle through the gasket strip and bringing said strip against said flange, and means for cutting the outer edge of the gasket.

4

11. In a machine of the class described, the combination, with means for supporting a strip of gasket material, of means for positioning on said strip a can nozzle having a flange at its upper end, means for turning said flange downward and thereby forming a burr at the upper end of the nozzle, and means for forcing the edge of the nozzle through the gasket strip, all at a single operation.

12. In a machine of the class described, the combination, with means for supporting a strip of gasket material, of means for po-

sitioning on said strip a can nozzle having a flange at its upper end, and a peripheral bead, of means for turning said flange downward and thereby forming a burr at the upper end of the nozzle, means for pressing said bead into an outwardly projecting flange, and means for forcing the edge of the nozzle through the gasket strip, all at a single operation.

In witness whereof, I have hereunto set my hand this 8th day of April 1922.

WILLIAM J. TOWLE.
